(57) **CLAIM**

The ornamental design for an interconnectable puzzle piece shaped note paper, as shown and described.

DESCRIPTION

FIG. 1 is a top view of an interconnectable puzzle piece shaped note paper showing my new design in an interconnected state;

FIG. 2 is a bottom view thereof;

FIG. 3 is a left side view thereof;

FIG. 4 is a right side view thereof;

FIG. 5 is a front view thereof;

FIG. 6 is a rear view thereof; and,

FIG. 7 is a bottom perspective view thereof, shown in a disconnected state.

The broken lines depict portions of the article that form no part of the claimed design.

1 Claim, 6 Drawing Sheets
